UNITED STATES PATENT OFFICE.

AUGUST I. HONDEVILLE, OF MERCED, CALIFORNIA, ASSIGNOR OF ONE-THIRD TO
FRANK M. FAGUNDES, JR., AND ONE-THIRD TO CHARLES A. VEREGGE, OF MERCED,
CALIFORNIA.

DEODORIZING DUST WHEEL.

Application filed March 26, 1928. Serial No. 264,808.

This invention relates to the fabric and clothes cleaning industry, and particularly a machine for deodorizing the fabrics after they have been cleaned with gasoline or the like, and for removing what is known in the industry as the gasoline dust which is still adhered to the fabrics.

The principal objects of my invention are to provide a machine for the purpose which 10 will deodorize any fabrics in a quick and thorough manner, which is extremely simple and inexpensive of construction as compared with other machines now in use and which enables the deodorized fabrics to be discharged as a unit from the machine instead of having to remove them piecemeal as is now the case.

A further object is to construct the machine so that it can operate with either air or water, 20 and can consequently be used as a washing machine as well as a deodorizer.

Another object is to construct the machine so that the air used in deodorizing the fabrics will not be drawn from the atmosphere 25 around the machine, but from a separate and segregated point in which the air may be kept in a thoroughly clean and pure condition.

While I have above specified the machine as being a deodorizing device, it is to be understood that its usefulness is not limited to 30 this purpose, since it also admirably serves as a drying room tumbler for laundries, for drying water-washed fabrics.

These objects I accomplish by means of 35 such structure and relative arrangement of parts as will fully appear by a perusal of the following specification and claims.

In the drawings similar characters of reference indicate corresponding parts in the 40 several views:

Fig. 1 is a sectional elevation of my improved deodorizer.

Fig. 2 is a cross section of the drum or tumbler of the machine.

Referring now more particularly to the characters of reference on the drawings, the 45 numeral 1 denotes suitable transverse end frames, adapted to rest on and be secured to the floor, and which are connected together 50 only at the back by cross braces 2. Supported on the end frames are journal boxes 3 in which are turnable cylindrical end trunnions 4 and 5 of the fabric receiving drum or tumbler cylinder 6, which is a solid wall

member throughout and preferably made of 55 a suitable grade of sheet metal. The trunnion 4 is in reality a large pipe, which opens freely into the adjacent end of the drum, the opening being preferably covered by a 60 screen 7.

This pipe leads any desired distance away 65 from the drum and serves as the air discharge passage therefrom. The trunnion 5 is also a pipe but does not open axially into the cylinder. Branching from said pipe 5 between 70 the drum and the adjacent bearing 3, however, is a plurality of conduits 8 (preferably four being employed) which conduits lead radially of the drum to the adjacent end at the inner periphery thereof. A deflector cone 8^a is 75 disposed in the pipe 5 just beyond the connections of the conduits therewith to cause the air passing into said pipe from its outer end to be distributed equally to all the conduits. At their drum ends these conduits are 80 connected to or formed integral with other conduits 9 which extend lengthwise of and inside the drum from end to end thereof. These conduits are preferably of rectangular form in cross section and are rigidly secured to 85 the drum in any suitable manner. Only one radial wall of each conduit 9 is freely perforated with rows of holes 10, the holes in the walls of the different conduits facing 90 in the same direction relative to the rotation 95 of the drum. The drum has a circumferentially sliding door 6^a of suitable character disposed between adjacent conduits 9 and extending for practically the full length of the drum.

The pipe 5 also has a driving pulley 11 mounted thereon and its outer end beyond the bearing 3 has a turnable running fitting with a stationary pipe 12 which leads from a blower or the like and which is supported from 100 the frame 1 by a bracket 13. A stuffing gland 14 of suitable character is associated with the adjacent ends of the pipe 5 and 12 to prevent leakage at the joint.

By reason of this construction it will be 105 seen that air blown through the pipe 12 will be discharged into the drum throughout its length through the conduit holes 10. On account of the positioning of the holes in the different conduits relative to each other, and 110 the location of the single discharge outlet, the air will take a whirling spiral movement through the drum from said holes to the out-

let, thus effectively acting on the fabrics in the drum to remove any odor and dust thereon. In order to equalize the air pressure throughout the length of the drum, the conduits are narrowed toward the discharge end of the drum as shown. Besides serving as air conduits, the members 9 function as baffles or ribs to catch and raise the fabrics in the drum somewhat with the rotation thereof. 10 This causes them to be tumbled and thrown about and thus intermittently held suspended and in position to be thoroughly exposed to the action of the whirling air currents.

The drum is rotated in the direction opposite to the direction of travel of the air currents from the openings 10, so that the fabrics when engaged and raised by the ribs will be forced by said ribs to move about the drum in a direction opposite to the flow of air, 20 and will be supported on the unperforated sides of the ribs. This prevents any possible choking of the opening by the fabrics and permits of a full and continuous flow of air being distributed from said openings to act 25 on the tumbling fabrics.

The end frames being braced only at the back enables a truck 15 to be wheeled between said frames from the front of the machine, so that upon rotating the drum so 30 that the door is inverted, and opening the latter, all the fabrics will be instantly discharged onto the truck without having to take them out a few at a time from the top of the drum.

35 The drum and intake air passages being entirely shut off from the atmosphere around the drum, the air supply for the drum may be kept segregated from such atmosphere, thus enabling only pure and clean air to be 40 discharged into the drum. This feature of construction also enables water to be used instead of air if desired, in the event that it is intended to use the machine for washing purposes.

45 From the foregoing description it will be readily seen that I have produced such a device as substantially fulfills the objects of the invention as set forth herein.

While this specification sets forth in detail 50 the present and preferred construction of the device, still in practice such deviations from such detail may be resorted to as do not form a departure from the spirit of the invention, as defined by the appended claims.

55 Having thus described my invention what I claim as new and useful and desire to secure by Letters Patent is:

1. A deodorizing machine comprising a closed drum, means for rotating the drum, longitudinally extending and circumferentially spaced conduits in the drum adjacent the inner periphery thereof, said conduits having openings therealong, means for passing air through the conduits, and an air discharge outlet from one end of the drum. 60 65

2. A deodorizing machine comprising a closed drum, means for rotating the drum, means for discharging air into the drum from adjacent the inner periphery thereof substantially throughout the length of the drum 70 at circumferentially spaced points, and an air discharge outlet from one end of the drum.

3. A deodorizing machine comprising a closed drum, means for rotating the drum, 75 longitudinally extending and circumferentially spaced conduits in the drum adjacent the inner periphery thereof, said conduits having openings therealong only on one radially disposed side thereof, means for passing air through the conduits and an air discharge opening from one end of the drum. 80

4. A structure as in claim 3, in which the direction of rotation of the drum is opposite to the direction of flow of air from the conduit openings into the drum. 85

5. A deodorizing machine comprising a closed drum, tubular end members connected thereto, journal supports for said members; one member opening freely to the drum but 90 the other one being axially closed to the drum, perforated conduits extending along the interior of the drum at the inner periphery thereof and in circumferentially spaced relation, means connecting said conduits to the other member, means for introducing air into the outer end of said other member, and means for rotating the drum. 95

6. A deodorizing machine comprising a closed drum, tubular end members connected thereto, journal supports for said members; one member opening freely to the drum but the other one being axially closed to the drum, perforated conduits extending along the interior of the drum at the inner periphery 100 thereof and in circumferentially spaced relation, means connecting said conduits to the other member, a stationary air supply pipe having a running fit with the outer end of said other member, and means for rotating 105 the drum. 110

In testimony whereof I affix my signature.

AUGUST I. HONDEVILLE.
